CLAIM

The ornamental design for a track for display shelving, as shown and described.

DESCRIPTION

FIG. 1 is a perspective view of a track for display shelving showing our new design;

FIG. 2 is a front view thereof, the rear view being a mirror image of the front view;

FIG. 3 is a side view thereof;

FIG. 4 is another side view thereof;

FIG. 5 is a top view thereof; and,

FIG. 6 is a bottom view thereof.

Where the figures show the article broken away, they are understood to indicate unclaimed length or width.
